UNITED STATES PATENT OFFICE.

WILLIAM P. McCORKINDALE, OF HOLYOKE, MASSACHUSETTS, ASSIGNOR TO EMILY K. DIETZ, OF PHILADELPHIA, PENNSYLVANIA.

TOWEL-DISPENSING CABINET.

1,351,956.

Specification of Letters Patent. Patented Sept. 7, 1920.

Application filed December 6, 1919. Serial No. 343,087.

To all whom it may concern:

Be it known that I, WILLIAM P. McCORKINDALE, a citizen of the United States of America, residing at Holyoke, in the county 5 of Hampden and State of Massachusetts, have invented certain new and useful Improvements in Towel-Dispensing Cabinets, of which the following is a specification.

This invention relates to improvements in 10 cabinets for dispensing paper towels and the like and consists particularly in the provision of a cabinet with a downwardly and forwardly opening door having a hinge connection to the body of the cabinet extending 15 along the bottom portion of the cabinet and providing one side or border of the delivery opening formed in the bottom of the cabinet.

With the above and other objects in view the invention consists in certain new and 20 useful constructions, combinations, and arrangements of parts clearly shown in the accompanying drawings in which:

Figure 1 is an end elevation.

Fig. 2 is a vertical sectional view thereof 25 showing the door in its open position.

Referring to the accompanying drawings 30 5 designates the back wall of the cabinet, 6 one end wall and 7 the opposite end wall and 8 the top wall which are rigidly connected to each other.

The back wall 5 is formed with a forwardly extending horizontal ledge 9 and a pintle rod 10 is disposed in parallel relation to the edge of said ledge 9 and connected 35 by angular terminal portions 11 to the end walls 6 and 7. The pintle rod 10 is spaced from the edge portion of the ledge 9 to provide a normally opened delivery opening 12 through which the towels may be withdrawn.

The front wall 13 is formed on its lower end with a horizontal flange 14 which is connected by means of hinge eyes 15 with the pintle rod 10 and this front wall is adapted 45 to open outwardly and downwardly and be supported in its open position wholly by the pintle rod 10.

The top wall 8 is formed or provided with 50 a pendant flange 16 which is engaged by the upper edge portion of the front wall 13 and

in order to retain said front wall or door in a closed position a U shaped member or the like 17 is positively fixed to the pendant ledge 16 and is adapted to extend through a slot 18 formed in the front wall 13. A padlock 19 is secured to the U shaped member 55 17 to hold the door in locked position.

The downwardly and forwardly opening door permits of a quick filling of the cabinet with a new supply of towels or the like and 60 also facilitates the removal of a supply of towels from the cabinet as the downward movement of the flange or ledge 14 permits the hand to be inserted under the towel stack or to be retained in this position during the 65 filling operation, thus insuring a neat and rapid positioning of the towels in the cabinet.

Having described my invention I claim:

A dispensing cabinet for paper towels and 70 the like consisting of a housing including side walls a top wall a rear wall and a bottom wall of less width than the width of the sides and extending from a point rearwardly of the center line of the container 75 to the back wall, a pintle secured at its ends to the side walls and located between the forward edge of said bottom wall and the forward edges of the side walls, a front wall having on its lower end an extension constituting a bottom wall portion in its normal position and hingedly connected with 80 said pintle, the front wall being adapted to be disposed against the forward edges of the side walls, and means for holding said front 85 wall in its closed position, the extension of said front wall when in its normal position being disposed substantially in the same plane as the bottom wall and its rear edge being spaced forwardly from the forward 90 edge of the bottom wall to provide a delivery opening, said container being adapted to receive a plurality of sheets so that the forward portions thereof will be supported by 95 said pintle and the extension of said front wall.

Signed by me at Springfield, Massachusetts.

WILLIAM P. McCORKINDALE.
